UNITED STATES PATENT OFFICE.

FRANK L. O. WADSWORTH, OF PITTSBURG, PENNSYLVANIA, ASSIGNOR TO WINDOW GLASS MACHINE COMPANY, OF PITTSBURG, PENNSYLVANIA, A CORPORATION OF NEW JERSEY.

METHOD OF AND APPARATUS FOR DRAWING GLASS.

No. 889,832.

Specification of Letters Patent.

Patented June 2, 1908.

Application filed July 9, 1906. Serial No. 325,265.

To all whom it may concern:

Be it known that I, FRANK L. O. WADSWORTH, of Pittsburg, Allegheny county, Pennsylvania, have invented a new and useful Method of and Apparatus for Drawing Glass, of which the following is a full, clear, and exact description, reference being had to the accompanying drawings, forming part of this specification, in which—

10 Figure 1 is a diagrammatic plan view of apparatus constructed in accordance with my invention; and Fig. 2 is a cross-section on an enlarged scale of the furnace partly in front elevation.

15 My invention relates to the drawing of glass articles, and is designed to do away with the feeding of glass from a tank into drawing pots or receptacles. It is also designed to obviate the removal of the remaining glass from drawing pots. The handling of cullet from the pots is done away with, as well as all operations connected with the feeding and transferring of glass in the present systems.

20 25 My invention consists in providing a series of pots into each of which the glass batch is fed, these pots being placed in a furnace in which the batch is melted and brought into proper condition for drawing. The pots are moved successively out of the furnace, the articles are drawn therefrom, the pots are then returned to the entrance end of the furnace, a fresh batch is fed thereinto, and the operation thus goes on continuously, without the necessity for cleaning the pots, for removing cullet, or for any transfer of glass from one receptacle to another.

25 30 35 In the drawing, 2 represents a furnace which may be similar to the ordinary tank furnace except that tracks 5 are provided which extend through it. The furnace is in the form of a tunnel having movable end doors 3 and 4 through which the carriers and pots move. The floor of the furnace in the form shown is provided with four tracks 5, upon which travel the trucks 6. These trucks are provided with bodies 7 of refractory material on which are set the pots 8. In order to protect the wheels and tracks, I 40 45 50 55 preferably provide refractory piers 9 extending between the tracks, the refractory car bodies having lateral extensions 10 which extend partly over the piers, thus protecting the metal parts. The cars may butt against each other end to end, or may be provided

with suitable connections. They may also be pushed through the furnace by hydraulic mechanism, at the rear end, or by any other suitable apparatus. From one end of the furnace, tracks 11 lead to the drawing stations 12. These tracks may be arranged so that the pots from any one track pass to certain stations, or so that the pots from any track may pass to any one of the drawing stations. From the four drawing stations the trucks return over tracks 13 to tracks 13, which extend through tunnels 14 back to the rear end of the furnace. From this point the return cars or trucks may be moved back onto the rear extensions of the furnace tracks, where they are fed with the batch material and again pushed into the furnace.

In the use of the apparatus, the furnace is preferably kept filled with the series of pots. As one pot is pushed or moved out from one track to a drawing station, another pot with a fresh batch of material will be fed in at the rear end on the same track. The length of the furnace is preferably such that allowing the proper time for drawing, the glass batch 80 will be properly melted, and fined, in the time of travel of the pot through the furnace. As the glass remaining in the pot is not removed, there need be no heating of the pot at the drawing station. The truck with the pot 85 thereon is simply moved out of the furnace to the drawing station, the glass drawn therefrom in any desirable manner, and the truck and pot then moved back through the return tunnel to the entrance end. The return tunnels are preferably employed in order to keep the refractory truck body and the pot at a high temperature, thus saving in fuel. I also 90 preferably apply heat to the return tunnels 14 in such a manner that there is a gradually increasing temperature from the drawing station end to the opposite end. The cars in returning through these tunnels will therefore be gradually heated up and will be at a high temperature when the batch is fed in 100 and the pot moved into the furnace proper.

The advantages of my invention will be apparent to those skilled in the art. In the ordinary drawing system, where ladling is employed, the glass must be ladled from the 105 furnace and the ladle then moved over to the drawing station and the glass partially emptied into a pot, which is usually reversible and is mounted in a furnace. The ladle is then moved to a cullet tank, into which the 110

remainder of the glass is emptied. The remaining glass after each draw is melted out from the lower cavity of the reversible pot, while the drawing of the glass from the upper cavity is taking place. This cullet glass must be returned to the furnace, as well as the cullet from the ladles. My invention does away with all of these operations, as well as all the cullet from ladles and pots. It 10 also does away with the reversible pots and with all the furnaces for melting out the cullet glass from the pots. After the drawing operation in my system, the remaining glass is left in the pot, and the batch is fed in upon it. There is no transfer of glass from one receptacle to another, and the entire operation is simple and easily carried out. Other mechanism may be used for carrying the pots through the furnace, as well as moving them 15 to the drawing stations and back to the entrance end of the furnace. The pots may be moved back through the furnace itself, through exterior tunnels, or through the open air.

20 Many other changes may be made in the form and arrangement of the apparatus without departing from my invention.

I claim:

1. A furnace having a series of glass-holding pots or receptacles, means for moving said pots successively through the furnace chamber, and a drawing station to which the pots are moved; substantially as described.
2. A furnace having a series of glass-holding pots arranged to move through said furnace successively, a drawing station to which the pots are movable, and means for returning the pots to the entrance end of the furnace; substantially as described.
3. A furnace having a series of pots, means for moving the pots successively through the furnace, and a series of drawing stations to which the pots are movable; substantially as described.
4. A furnace having a track extending therethrough, a series of trucks or carriages having pots mounted thereon and movable through the furnace, and a drawing station at one point in the track; substantially as described.
5. A glass melting furnace comprising a heating chamber, a series of pots and means to move the pots through the furnace in succession, and a drawing station in the path of the pots.
6. A glass melting and fining furnace having a series of pots movable through the melting and fining furnace, and a drawing station to which the pots are movable; substantially as described.
7. A furnace having a track extending therethrough, trucks having pots thereon movable along said tracks, a drawing station at one point in the track, and return track 55 on which the trucks may be returned to the

entrance or melting end of the furnace; substantially as described.

8. A furnace having a series of pots, a batch-receiving station, and melting furnace, and means for moving the pots from the 70 batch-receiving station through the melting furnace; substantially as described.

9. A furnace having a series of pots, a batch-receiving station, a melting furnace, a drawing station, and means for moving the 75 pots from the batch station through the furnace, said pots being movable to the drawing station; substantially as described.

10. A furnace having a track, a series of trucks having glass-holding pots thereon, 80 and a batch station, a melting furnace, and a drawing station at different points in the length of the track; substantially as described.

11. The method of making glass, consisting in feeding the batch into a series of pots, and moving said pots successively through a melting furnace; substantially as described.

12. The method of making glass, consisting in feeding the batch into a series of pots, 90 and moving said pots through a melting and fining furnace; substantially as described.

13. The method of making glass articles, consisting in feeding the batch into a series of pots, moving said pots successively 95 through a melting furnace, and drawing glass from the successive pots; substantially as described.

14. The method of making glass articles, consisting in feeding the batch into a series 100 of pots, moving the said pots successively through a melting furnace, drawing glass from the successive pots, and returning said pots to the batch station; substantially as described.

15. The method of drawing glass articles, consisting in drawing glass from a bath in a pot, leaving a portion of glass in the pot, filling in a fresh batch, remelting the glass therein, and again drawing glass from the pot; 110 substantially as described.

16. The method of making glass articles, consisting in melting a batch in a pot, drawing glass directly from the pot, refilling the pot with a batch, and remelting; substantially as described.

17. The method of forming glass articles, consisting in feeding a batch into a series of pots, moving the said pots successively through a melting and fining furnace, and 120 then to a drawing station, drawing glass successively directly from said pots, and then returning said pots successively to the entrance or melting end of the furnace; substantially as described.

18. The method of forming glass articles, consisting in feeding a batch into a series of pots, moving the said pots successively through a melting and fining furnace, and then to a drawing station, drawing glass suc- 130

cessively directly from said pots, then returning said pots successively to the entrance or melting end of the furnace, and reheating the pots as they are moved back to the batch 5 station; substantially as described.

19. The combination of a glass heating furnace, a continuous track passing through the furnace, and a series of pots movable through the furnace on said tracks.

20. The combination of a furnace provided with a track therethrough, a series of trucks provided with means to protect the wheels from the heat of the furnace and each carrying a pot, a drawing station and means

to move the pots through the furnace to the 15 drawing station and return into the furnace.

21. The combination with a heating furnace and a circuit of track running therethrough, of a series of trucks carrying pots movable on said track, and a drawing station 20 located on the circuit of the track, substantially as described.

In testimony whereof, I have hereunto set my hand.

FRANK L. O. WADSWORTH.
